FRED E. YOUNGS, OF DETROIT, MICHIGAN.

PIPE-BENDING TOOL.

1,251,610.

Specification of Letters Patent. Patented Jan. 1, 1918.

Application filed July 8, 1915. Serial No. 38,744.

To all whom it may concern:

Be it known that I, FRED E. YOUNGS, a citizen of the United States, residing at Detroit, in the county of Wayne and State of Michigan, have invented a new and useful 5 Pipe-Bending Tool, of which the following is a specification.

Pipe bending tools heretofore in use have been objectionable because they failed to insure a grip sufficient to prevent slipping 10 longitudinally in respect to the pipe being bent, and were, in this respect, a source of constant annoyance and danger to the user, particularly in those instances in which the work was being done in elevated places; 15 they have also been objectionable in that the fixed relation of the handle to the bending jaws so limited the conditions under which a single tool could be used as to render it necessary to employ two or more in which the handles were arranged at different 20 angles in respect to the jaws.

The present invention relates to a device wherein the force applied in bending the pipe is utilized to cause a strong gripping 25 effect upon the pipe itself, and whereby the capacity for forming bends at various angles is greatly increased; and it consists in a tool having a fixed jaw arranged to extend 30 longitudinally of the pipe, and a second jaw spaced from the first and pivoted to swing 35 about an axis at substantially right angles to the fixed jaw. The invention further consists in the details of construction shown, described and particularly pointed out in the claims.

In the drawings, Figure 1 is a plan view 40 of a preferred embodiment of the invention. Fig. 2 is a side view thereof. Fig. 3 is a plan view showing the movable jaw in 45 gripping relation to the fixed jaw. Fig. 4 is an inverted plan view of the movable jaw, partly in section. Fig. 5 is a side elevation thereof.

Similar reference characters refer to like parts throughout the several views.

In the embodiment of my invention shown, 1 indicates a socket or base in which a handle 2 is received and retained by 50 screws 3. Formed integrally with the socket and preferably extending at an angle therefrom is a fixed jaw member 4 having its outer end turned to one side to form the jaw 5, the central portion of the inner face of 55 which is preferably curved or arched outwardly as indicated at 6. It will be noted

that the arched portion merges at each end into the elements 7, preferably concave to the radius of the pipe, the axis of the concave portions preferably being inclined 60 slightly in respect to the base line of the arched portion 6 for a purpose hereinafter indicated.

The socket member is cut away opposite the fixed jaw to form a bearing between the 65 fixed jaw member and the ear 8 for the cylindrical shank 9 of a movable jaw 10, the central portion of the inner face of which is also preferably concave as indicated at 11; and from the bases of the concave portion the inner face is flared or convexly curved outwardly, forming the pipe bearing surfaces of the bending and clamping lips 12. The curving of the movable jaw at the ends and the arching of the center portion of the fixed jaw is to permit the tool to be taken off of a bent pipe or replaced to change the bend without having to slide it along to a straight portion of the pipe; in other words, assuming that the 70 fixed and movable jaws are so spaced as to slip onto a straight pipe from the side with slight clearance, it would be impossible to withdraw it by a reverse action after the pipe is bent except upon first sliding it along 75 to a straight portion of pipe—the general curve determined by the clamping surfaces corresponds close enough to the final curve of the pipe to avoid this difficulty. The shank 9 is provided with a perforation 13 80 through which loosely passes a retaining pin 14. Shoulders 15, between the ear 8 and the fixed jaw member, limit the swinging movement of the movable jaw on its bearing. On 85 its face, adjacent the fixed jaw member, the movable jaw is provided with the ears 16 which allow the surfaces of the lips 12 to be brought flush with the adjacent surface of the fixed jaw member (Fig. 2); and on 90 its opposite face the movable jaw may be reinforced by the rib 18.

In use, the tool is slipped onto the pipe from the side in the ordinary manner, the rib 18 serving to adjust the jaw parallel thereto and to facilitate entering the pipe 105 under the hook of the fixed jaw, that is, the rib strikes the pipe, which then stands about perpendicular to the plane of Fig. 2, and tends to swing the jaw into parallel relation to the pipe. Pressure now being applied 110 to swing the handle longitudinally in either direction, the pipe becomes seated against

the concave surface 7 at the opposite end of the fixed jaw and against the surface 12 on the end of the movable jaw toward which the handle is being swung. The pressure 5 on this end of the pivoted jaw turns the latter in its bearing and causes its opposite end to grip the pipe rigidly against and substantially throughout the surface 7, which being of appreciable area, insures a 10 large amount of friction without danger of crushing the pipe, whereby the tendency of the tool to slip longitudinally of the pipe is effectually overcome, whereupon a further 15 swinging of the handle causes the bending to take place in the usual way.

Since both ends of the jaws are similar and since the handle may be swung longitudinally of the pipe in either direction, effective bending engagement of the jaws 20 with the pipe takes place with the handle at two different angles to the pipe, the number of degrees the movable jaw travels from the center or entering position being either added to or subtracted from the obliquity 25 of the handle. Thus, assuming that the handle is set at $67\frac{1}{2}$ degrees to the fixed jaw and that the movable jaw may swing $12\frac{1}{2}$ degrees either way from the center, the tool comes into effective bending engagement 30 with the pipe when the angle of the handle to the pipe on the side and in the direction toward which it moves will be either 55 or 100 degrees. The tool may, therefore, be applied in one position and swung until 35 the handle nearly reaches the pipe, and may then be reversed, whereupon the handle will stand away from the pipe and may again be swung to complete the bend; consequently, the device is especially adapted for 40 use in cramped positions where a tool with only one working angle would be inadequate.

While throughout the specification and claims this tool is spoken of as for bending 45 pipe, it is to be understood that it is of equal value for bending solid bars and for which it is also intended for use. The word "pipe" which appears in the claims therefore includes, for want of a more generic term, 50 both pipes and solid rods and in no sense limits the claims to tools for bending bars of tubular cross section. It is also clear that the details of the device may be changed considerably without departing from the spirit 55 of my invention; for example, the handle 2 and base 1 may in some instances be made in one piece. I do not, therefore, wish to be limited otherwise than as indicated by the subjoined claims.

60 I claim:—

1. A pipe bending tool comprising a base including a body portion and a fixed jaw extending at an angle therefrom, and a movable jaw spaced from the fixed jaw to allow 65 the tool to be slipped onto a pipe from the

side, said movable jaw being arranged to normally swing in respect to the fixed jaw in the plane in which the pipe is to be bent and having two gripping surfaces arranged on opposite sides of the axis about which the 70 jaw swings, whereby, when the base is swung longitudinally of the pipe, contact of the pipe with one of the gripping surfaces swings the movable jaw and causes its other 75 surface to grip the pipe against the corresponding end portion of the movable jaw to insure a strong frictional engagement of the tool thereon.

2. A pipe bending tool comprising a base including a body portion and a fixed jaw 80 extending at an angle therefrom, and a movable jaw spaced from the fixed jaw to allow the tool to be slipped onto a pipe from the side, the end portions of the movable jaw being concave or flared to afford pipe engaging areas of considerable size, said movable 85 jaw being arranged to normally swing in respect to the fixed jaw and having its corners on the side opposite the body portion diverging away from each other and away from the fixed jaw to allow the tool to be readily removed from a curved pipe.

3. A pipe bending tool comprising a base, a body portion and fixed jaw member extending at an angle therefrom, and a movable jaw located between the base and the fixed jaw and spaced from the latter to allow the tool to be slipped onto a pipe from the side, said last mentioned jaw being arranged to normally swing in respect to the fixed jaw, 95 about an axis at an angle to the plane in which the pipe is to be bent, the movable jaw having pipe engaging surfaces near its ends arranged substantially symmetrically about the axis about which the movable jaw swings, 100 whereby, when the base is swung longitudinally of the pipe, contact of the pipe with one end of the movable jaw swings the movable jaw and forces its other end against the pipe to insure a strong frictional grip of the 110 tool thereon.

4. A pipe bending tool comprising a base, a body portion and fixed jaw member, a bearing formed in the body portion, a movable jaw located between the base and the 115 fixed jaw and spaced from the latter to allow the tool to be slipped onto a pipe from the side, said last mentioned jaw being arranged to normally swing on the bearing in the plane in which the pipe is to be bent, means 120 for retaining the movable jaw in position on the bearing, said movable jaw having two pipe engaging surfaces, one near each end of said jaw, the whole arrangement being such that contact of the pipe with one 125 end of the movable jaw swings the movable jaw and forces its other end against the pipe to insure a strong frictional grip of the tool thereon.

5. A pipe bending tool comprising a base, 130

- a body portion and fixed jaw member, a bearing formed in the body portion, a movable jaw located between the base and the fixed jaw and spaced from the latter to allow
5 the tool to be slipped onto a pipe from the side, said last mentioned jaw being arranged to swing on the bearing and having two pipe gripping surfaces, one near each end of said movable jaw, said surfaces being both lo-
10 cated nearer the fixed jaw than the axis about which the movable jaw swings, means for retaining the movable jaw in position on the bearing, means for limiting the swinging movement of the movable jaw, the whole ar-
15 rangement being such that contact of the pipe with one end of the movable jaw swings the movable jaw and forces its other end against the pipe to insure a strong frictional grip of the tool thereon.
20 6. A pipe bending tool comprising a base, a body portion and fixed jaw member ex-
tending at an angle therefrom, a cylindrical bearing formed in the body portion, a movable jaw located between the base and the
25 fixed jaw and spaced from the latter to allow the tool to be slipped onto the pipe from the side, said last mentioned jaw having a por-
tion conforming to and received on the cylin-
drical bearing, said portion being perforated, and a pin passing loosely through the 30 perforation for retaining the movable jaw in position, the whole arrangement being such that contact of the pipe with one end of the movable jaw swings the movable jaw and forces its other end against the pipe to 35 insure a strong frictional grip of the tool thereon.
7. A pipe bending tool including a base comprising a body portion and a fixed jaw, a movable jaw spaced from the fixed jaw to 40 allow the tool to be slipped onto the tool from the side, said movable jaw being ar-
ranged to normally swing in the plane in which the pipe is to be bent and about an axis substantially opposite the mid-point in 45 the length of the movable jaw, said movable jaw and said fixed jaws having coöperating gripping surfaces at each end, and a handle for the tool arranged substantially in the plane in which the pipe is to be bent and at 50 an acute angle to the line joining the center of the fixed jaw and the axis about which the movable jaw swings.

In testimony whereof I have signed this specification.

FRED E. YOUNGS.
